US00D780385S

(12) **United States Design Patent** (10) **Patent No.:** **US D780,385 S**
Jakubowski (45) **Date of Patent:** **** Feb. 28, 2017**

(54) **PET STEP**

- (71) Applicant: **Vermont Juvenile Furniture Mfg., Inc.**, West Rutland, VT (US)
- (72) Inventor: **Chris Jakubowski**, Rutland, VT (US)
- (73) Assignee: **Vermont Juvenile Furniture Mfg., Inc.**, West Rutland, VT (US)
- (**) Term: **15 Years**
- (21) Appl. No.: **29/542,603**
- (22) Filed: **Oct. 15, 2015**
- (51) LOC (10) Cl. **30-03**
- (52) U.S. Cl. **USPC D30/199**
- (58) **Field of Classification Search**

CLAIM

The ornamental design for a pet step, as shown and described.

DESCRIPTION

FIG. 1 is a top, front, right perspective view of a pet step in accordance with my design;
 FIG. 2 is a bottom, rear, right perspective view thereof;
 FIG. 3 is a top plan view thereof;
 FIG. 4 is a front elevational view thereof;
 FIG. 5 is a right side elevational view thereof;
 FIG. 6 is a bottom plan view thereof;
 FIG. 7 is a left side elevational view thereof;
 FIG. 8 is a rear elevational view thereof; and,

(Continued)

FIG. 9 is a cross-sectional view thereof taken along line 9-9 in FIG. 3, with the two lower struts removed for clarity.

1 Claim, 9 Drawing Sheets
